AUGUST RASMUS BALTZER, OF MILWAUKEE, WISCONSIN, ASSIGNOR OF ONE-HALF TO
CARL H. CRAWFORD, OF CHICAGO, ILLINOIS.

METHOD FOR CONSTRUCTING CONCRETE BUILDINGS.

1,035,826.

Specification of Letters Patent. Patented Aug. 13, 1912.

Application filed August 2, 1909. Serial No. 510,768.

To all whom it may concern:

Be it known that I, AUGUST RASMUS BALTZER, a citizen of the United States, residing at Milwaukee, in the county of Milwaukee and State of Wisconsin, have invented new and useful Improvements in Methods for Constructing Concrete Buildings, of which the following is a specification.

10 This invention relates to an improved method for constructing buildings of reinforced concrete.

One of the objects of the invention is to provide a rolling wall supporting structure 15 which may serve, either by gravity, or by the application of power, to swing the wall from a substantially horizontal position into a vertical position and on to the foundation therefor.

20 The invention will be more fully described in connection with the accompanying drawing and will be more particularly pointed out and ascertained in and by the appended claims.

25 In the drawing:—Figure 1 is a view partly in section of a wall and foundation with the improved device of my invention shown in the position which it would assume when the wall is being placed in position. Fig. 2 is a similar view showing the device of my invention in the position which it assumes when the wall is being formed and permitted to set. Fig. 3 is a rear elevation with the parts in the position shown 30 in Fig. 2. Fig. 4 is a diagrammatic view of a modified form of the invention in which power is applied to swing the wall from a forming or horizontal position into a vertical position. Fig. 5 is a sectional view on line 5—5 of Fig. 1.

40 Like characters of reference designate similar parts throughout the different figures of the drawing.

As shown a support or foundation is indicated at 1, the cellar at 2, and the wall at 3, and the wall of an adjacent building at 4.

45 A supporting or track structure 5 is disposed in the cellar 2 and includes uprights 6 and 7 upon which a track bar or member 8 is disposed. In the form shown the upright 7 is somewhat higher than the upright 6 so as to incline the track support 8. In the

form shown a rack 9 is mounted on the track bar 8.

A rolling wall supporting and positioning device is indicated as a whole at 10 and the same may consist of a segmental trussed structure provided with a peripheral portion 11, having teeth 12, adapted to mesh with the teeth of the rack 9. A plurality of these segmental supporting structures will be arranged in suitable parallel relation spaced suitable distances apart in accordance with the length of the wall, as clearly shown in Fig. 3. Each of said rolling structures may be provided with a trussed member 13, and these trussed members 13 may be provided with extensions 14, detachably secured thereto, as at 15. A plurality of different lengths of extensions 14 may be provided to accommodate walls of different heights.

75 The trussed member 13 may be connected by transversely disposed members, in the form of channel-irons 16, on which a bed-structure of boards or the like 17, may be disposed, to receive the concrete or other material of which the wall is to be formed. The boards 17 constitute the concrete bed and may be provided with end boards 18, 80 one only being shown, which is adapted to be held in place during formation of the wall by a removable foot portion 19.

A convenient means for anchoring the boards 17 and channels 16 to the members 85 13 may consist of bolts 20, extending through the members 13, and channels 16, and boards 17 into the wall 3, and the nuts 21 embedded in the wall 3 as shown in Fig. 1. After the wall is positioned on to the 90 foundation the heads 22 of the bolts 20 may be turned to disengage the bolts from the nuts 21, thereby leaving the nuts in the wall, and permitting the structure to be rolled away from engagement with the wall.

95 The several structures 10 may be suitably connected as indicated at 23, so as to form a unitary structure.

It will be obvious that when the rack 9 is set at an incline the center of gravity will 100 be so disposed as to cause the rolling structure 10 to normally seek the position shown in Fig. 1, and position the wall by gravity on to its foundation. However if the upper

portion of the wall projects above or beyond the structures 10, at *a*, a sufficient distance to prevent the structures 10 from moving by gravity to the position shown in Fig. 1, 5 means may be provided in the form of weights 24, to insure movement of the structures 10 in the direction necessary to position the wall upon the foundation.

The weights 24 may be in the form of 10 blocks as shown and may be bolted, by bolts 25, so that any desired number of weights may be employed according to requirements.

Means is provided for controlling the rolling 15 movement of the structures 10, when the wall is being positioned, and said means is herein diagrammatically indicated in the form of a restraining cable 26, which may be connected at 27, and controlled by a windlass 28, or other suitable device in any convenient manner.

A modified form of the invention is shown in Fig. 4, diagrammatically, wherein the rolling bed supporting structure 29 is disposed upon a horizontally arranged track 25 structure 30. In order to roll the structure 29 into a position to place the wall upon a foundation, power may be applied to a device 31.

It will be seen that my improved method 30 and apparatus may be used to great advantage in positioning a wall upon a foundation which is closely adjacent to a finished structure, in view of the fact that a wall may be positioned upon its foundation without being projected upon the vertical plane thereof 35 outwardly, and it will also be apparent that even though the wall were in practical contact with an adjacent finished structure it could be positioned upon its foundation 40 without any interference therewith.

It will be further obvious that in view of the fact that the wall is supported from its inner surface, in the process of formation, any desired exterior finish may be carried 45 out in the process of forming the wall.

It will be further obvious that the wall may be positioned wholly by gravity thereby avoiding the necessity of providing any form of operating means.

50 In order to accurately position the wall on the foundation 1 adjusting means may be provided for the rolling or arcuate structure 10. In the embodiment shown the racks 9 are mounted on anti-friction rollers 32 disposed in a run-way 33 and plates 34 serve to keep the rollers in position laterally and also keep the structures 10 in alinement with the racks 9. The racks 9 are connected with levers 35 (one being shown) pivoted at 36 55 to the upright or standard 7. A yoke 37 is pivoted to the standard 7 and embraces the lower end of the lever 9 and carries an adjusting screw 38, provided with a hand wheel 39, whereby longitudinal adjustment 60 may be imparted to the racks 9.

In accordance with my invention, the wall is progressively and bodily shifted toward a predetermined support or foundation on constantly changing points or bases of support, into a vertical position and onto the 70 support or foundation.

I claim:—

1. A method of constructing concrete buildings which consists in supporting a concrete wall in a suitable position inside 75 the foundation during formation, and in placing said wall upon a foundation by gravity without projecting the wall outside the vertical plane of said foundation.

2. A method of constructing concrete walls 80 which consists in supporting and forming in a substantially horizontal position a complete concrete wall of the desired height, and in progressively and bodily shifting all portions of the wall simultaneously toward a predetermined support and toward and into a vertical position and in finally positioning said wall in a permanent position on such support at the completion of such shifting movement and when the wall has assumed a vertical position.

3. A method of constructing concrete walls 85 which consists in supporting and forming in a substantially horizontal position, in a mold body, a concrete wall, and in progressively and bodily shifting said mold body and the wall on different and changing bases of support toward and into a permanent vertical position.

4. A method of constructing concrete walls 90 which consists in supporting and forming a concrete wall on a mold body disposed in a substantially horizontal position, and in progressively and bodily shifting said mold body and its wall on different bases of support successively approaching a foundation, with the wall and mold body finally assuming a vertical position, and in permanently placing the wall upon such foundation at the completion of such shifting movement.

5. A method of constructing concrete walls 95 which consists in supporting and forming in a substantially horizontal position a concrete wall of the desired height, and in progressively and bodily shifting all portions of the wall simultaneously toward a vertical position on to a predetermined support and restricting the complete shifting cycle of the wall to a predetermined course of movement from the starting to the final positioning of 100 the wall.

6. A method of constructing concrete walls 105 which consists in supporting and forming a concrete wall on a mold body disposed in a substantially horizontal position, and in progressively and bodily shifting said mold with its wall on different bases of support gradually approaching a foundation, and with the entire shifting operation restricted to a predetermined direction and character 110

of movement toward a vertical position, and in finally and permanently placing said wall upon the foundation at the completion of such shifting movement.

5 7. The method of making concrete walls for buildings which consists in forming a wall in a mold disposed in a substantially horizontal position to properly set the concrete, and in shifting the wall and mold 10 through a predetermined cycle of movement consisting in simultaneously moving all parts of the mold and wall bodily in a substantially horizontal direction, and in causing all of the parts of the wall and mold to 15 simultaneously and gradually assume a vertical position during such bodily horizontal movement to position the wall upon the foundation.

8. The method of making and erecting 20 concrete walls for buildings which consists of forming a wall in a mold disposed in a substantially horizontal position to properly set the concrete, with that portion of the mold that carries the bottom edge of the 25 wall located out of contact with the foundation, and in then bodily moving the mold and the wall upon constantly changing points of support toward said foundation and bringing said wall to a vertical position and depositing said wall upon said foundation.

9. The method of making and erecting

concrete walls for buildings which consists of forming a wall in a mold disposed in a substantially horizontal position and in then 35 bodily moving the mold and the wall upon constantly changing points of support toward a previously constructed permanent foundation and bringing said wall to a vertical position and depositing said wall upon 40 said foundation, said wall being positively guided during such movement to properly position it in a predetermined relation upon the foundation.

10. The method of making and erecting 45 concrete walls for buildings which consists of forming a wall in a mold disposed in a substantially horizontal position, and in then bodily moving the mold and the wall upon constantly changing points of support 50 toward a previously constructed permanent foundation and bringing said wall to a vertical position and depositing said wall upon said foundation, said wall being positively guided during such movement by means located entirely below the outer face of the 55 wall to properly position it in predetermined relation upon the foundation.

In testimony whereof I affix my signature in presence of two witnesses.

AUGUST RASMUS BALTZER.
